(57) CLAIM

The ornamental design for crystal candleholder, as shown and described.

DESCRIPTION

The patent or application file contains at least one drawing executed in color. Copies of this patent or patent application publication with color drawing(s) will be provided by the U.S. Patent and Trademark Office upon request and payment of the necessary fee.

FIG. 1 is a top view of the design of crystal candleholder with candles.

FIG. 2 is a perspective view of the lower side in front and the higher side in the back thereof;

FIG. 3 is a side view with the higher side in the front thereof;

FIG. 4 is a side view with a lower side in the front thereof;

FIG. 5 is a side perspective view of the lower and middle side in front thereof; and,

FIG. 6 is a perspective view of an alternate embodiment thereof, the only difference being in the omission of candles.
